COOLING SYSTEM

Victor C. Huntington, Blue Island, Ill., assignor
to Wepsco Steel Products Co., Blue Island, Ill.,
a corporation of Illinois

Application October 20, 1933, Serial No. 694,389

13 Claims. (Cl. 62—116)

This invention relates in general to mechanical refrigeration, and while the principles thereof may be utilized in apparatus of various sizes and characters for many purposes, my invention particularly is adapted for liquid dispensers and commonly known as bars.

One of the deterrent factors of mechanical refrigerated bars has been the difficulty of maintaining a constant, predetermined temperature 10 brine tank under varying outside temperatures and different quantities of draft service and to maintain an average predetermined temperature in a storage compartment from the same system of mechanical refrigeration.

15 The primary purpose of my present invention is the controlling of temperatures in a brine tank with less variation than was heretofore possible and simultaneously to control the temperature of one or more storage compartments from the same 20 mechanical refrigeration system.

While my invention is not restricted in particular to bars or any particular type of refrigeration apparatus, I have, for purposes of illustration, merely shown and described herein a simple system of the compressor type with a single storage compartment and one brine tank as illustrative of my invention.

Other objects and advantages of this invention will become apparent from the following detailed description with reference to the accompanying drawing.

On the drawing:

Figure 1 is a diagrammatic illustration of a refrigerating system incorporating my invention, 35 some of the parts being shown in section.

Figure 2 is a vertical section through the beverage cooler, some of the parts being shown in elevation.

As shown on the drawing:

40 The refrigerating apparatus diagrammatically illustrated in Figure 1 comprises a pump or compressor 5 driven by an electric motor 6 by electricity received from power lines 7 and 8, the line 7 adapted to be interrupted by a switch 9 interposed therein and controlled by a thermostatic element 10 connected thereto by a usual tube 12 which carries the expansible medium. The pump or compressor 5 is adapted to receive refrigerant through the intake connector 15 and discharge compressed refrigerant through the pipe 16 to the condenser 17 from where it passes through the receiver 18. A pipe 19 leads from the receiver 18 to an expansion valve 21 from which expanding refrigerant is adapted to pass 45 through the T 22 to the pipe 23 and the heat-absorbing device consisting of a coil 24 and a multiplicity of fins 25 disposed thereon for extracting heat from the storage chamber 26. The refrigerant from the heat-absorbing device indicated generally by the numeral 27 passes

through the pipe 28 and to the cooling coil 29 disposed in a brine tank 31 adjacent one end of the storage chamber 26. From the cooling coil 29 the refrigerant, which has passed through the coil 29, returns to the compressor 5 through the pipe 33. The inlet to the cooling coil 29 is preferably at the top and the outlet at the bottom which facilitates the formation of ice in the form shown in Figure 2.

Between the T 22 and the end of the pipe 28 there is a bypass comprising pipes 34 and 35 which are connected by an electrically operated valve 36 actuated by electricity from electric conductors 37 and 38 which in turn receive electric power from line wires 39 and 41, but are adapted to be interrupted by a controllable temperature responsive device 42 disposed in the storage chamber and adapted to operate at a predetermined minimum temperature for opening the valve 36 to permit refrigerant to bypass the heat-absorbing device 27 and circulate directly to the cooling coil 29 in the brine tank 31. The switch or temperature responsive device 42 is adapted to be actuated also at a predetermined maximum temperature for causing the valve 36 to close and require the refrigerant to pass through the heat-absorbing device 27 in series with the coil 29 in the brine tank 31. For actuating the expansion valve 21, there is provided a temperature responsive device 45 secured in contact with the pipe 33 by a clamp 46 which device 45 is directly affected by the temperature of the pipe 33 and thereby controls the opening and closing of the expansion valve 21 by the action of an expansible fluid passing thru a pipe 48.

The storage chamber 26 is provided with relatively heavy walls for limiting the infiltration of heat therethrough and thereby assisting the maintenance of a substantially constant temperature therein. The chamber 26 is designed 40 and intended for the storage of liquids, such as beverages and the like, which should be maintained at relatively low temperature, but preferably above freezing temperature. Beverages and the like may be stored in the chamber 26 in 45 barrels or kegs and may be removed for use as desired. The brine tank 31 is somewhat exaggerated in the drawing as compared with the size of the storage chamber 26. This tank is intended to be maintained at a relatively lower 50 temperature than the chamber 26 for the purpose of cooling beverages in the coil 52. The coil 52 is provided with an entrance connection 53 and a discharge pipe 54 from which the beverage may be drawn as dispensed in small quantities. The coil 52 is preferably disposed adjacent the bottom of the brine tank 31 at a point 55 spaced well below the cooling coil 29 in order that the brine 56, in which the coil 52 is im-

mersed, will not solidify about the coil 52. The cooling coil 29 is disposed above the coil 52 and is adapted to reduce the temperature of the brine 56 sufficiently to solidify the brine around the edges of the tank adjacent the top as indicated at 57 and 58. As best shown in Figure 1, the temperature responsive device 10 is held in a predetermined definite spaced relation with the coil 29 by a suitable bracket 61. Again referring to Figure 2, the temperature responsive device 10 is shown in contact with the solidified brine 58 and at which point the device 10 is adapted to be operated for actuating the switch 9 and stopping the operation of the electric motor 6. By this arrangement it will be appreciated that a predetermined amount of solidification of the brine in the tank 31 is permitted, which serves to maintain the brine at a constant temperature regardless of fluctuations in the temperature of the storage compartment 26 which may be occasioned by the transfer in or out of stored beverages.

In the operation of this refrigerating mechanism, the switch 9 being closed, the motor 6 will drive the compressor 5 through the medium of the driving connection 4, for compressing the refrigerant and storing it in the receiver 18. When the temperature of the pipe 33 is above a predetermined maximum, the device 45 will cause the opening of the expansion valve 21 permitting the discharge of condensed refrigerant to the pipe 19 and into the T 22 from which it may discharge through the heat-absorbing device 27 and in series through the cooling coil 29 and back to the compressor through the pipe 33. When the temperature of the storage chamber 26 becomes reduced to a predetermined minimum, the temperature responsive device 42 opens the circuit through the electrical conductors 37 and 38 causing the electrically operated valve 36 to open and bypass refrigerant through the pipes 34 and 35 directly to the cooling coil 29 and back to the compressor. This arrangement permits the cooling of the brine within the tank 31 to a temperature such that the brine will solidify at the top around the coil 29 until a predetermined degree of solidification has been effected, which is determined by the position of the temperature responsive device 10. When the solidified brine engages the device 10, the switch 9 is caused to operate for opening the conductor 7 and causing the driving motor 6 to stop and remain stopped until the solidified brine again recedes from the device 10, at which time the switch 9 is again closed causing further operation of the compressor. The thermostatic device 10 is preferably positioned sufficiently close to the wall of the tank 31 to permit the ice to melt away and the compressor to be started in the event of unusually high temperatures in the chamber 26 such as might occur after the doors of said chamber had been left open an unusually long time.

From the foregoing it will be apparent that the temperature in the coil 52 is controlled very accurately, the relative temperature thereof depending upon the density of the brine in the tank 31. For cooling beverages such as beer, a sweet-water brine has been found to have a proper density to maintain the coil 52 at a desired temperature. By varying the density of the brine or liquid in the tank 31, it is of course possible to vary the temperature at which the liquid surrounding the coil 52 is maintained,

since such temperature is a direct function of the freezing point of the brine or liquid.

I claim as my invention:

1. In a refrigerating system, a storage chamber, a heat-absorbing device in said chamber, a beverage cooler comprising a cooling coil, said cooler having a brine therein adapted to solidify about the cooling coil, means for supplying a refrigerant to said heat-absorbing means and thence to said cooling coil, means controlled by the temperature of the storage chamber to bypass the refrigerant directly to the cooling coil, and means responsive to a predetermined amount of solidification of the brine for stopping operation of the refrigerant supplying means. 15

2. In a refrigerating system, a storage chamber, a heat-absorbing device in said chamber, a beverage cooler comprising a cooling coil, said cooler having a brine therein adapted to solidify about the cooling coil, means for supplying a refrigerant to said heat-absorbing means and thence to said cooling coil, means controlled by the temperature of the storage chamber to bypass the refrigerant directly to the cooling coil, an expansion valve for controlling the admission of refrigerant to the cooling coil, and means responsive to temperature of the refrigerant discharged from the cooling coil for controlling the actuation of said expansion valve. 20

3. In a refrigerating system, a storage chamber, a heat-absorbing device in said chamber, a beverage cooler comprising a cooling coil, said cooler having a brine therein adapted to solidify about the cooling coil, means for supplying a refrigerant to said heat-absorbing means and thence to said cooling coil, means controlled by the temperature of the storage chamber to bypass the refrigerant directly to the cooling coil, and means responsive to a predetermined amount of solidification of the brine for stopping operation of the refrigerant supplying means, an expansion valve for controlling the admission of refrigerant to the cooling coil, and means responsive to temperature of the refrigerant discharged from the cooling coil for controlling the actuation of said expansion valve. 30

4. In a refrigerating system, a beverage cooler, comprising a brine container for containing brine adapted to freeze at a predetermined temperature, a cooling coil disposed in the upper part of said container, means for supplying refrigerant to said cooling coil, temperature responsive means adapted to be actuated upon a predetermined degree of solidification of the brine for stopping operation of the refrigerant supplying means, and a coil disposed adjacent the bottom of said brine container for containing beverage to be cooled. 50

5. In a refrigerating system, a beverage cooler, comprising a brine container for containing brine adapted to freeze at a predetermined temperature, a cooling coil disposed in the upper part of said container, means for supplying refrigerant to said cooling coil, temperature responsive means adapted to be actuated upon a predetermined degree of solidification of the brine for stopping operation of the refrigerant supplying means, a coil disposed adjacent the bottom of said brine container for containing beverage to be cooled, an expansion valve for controlling the admission of refrigerant to the cooling coil, and means responsive to temperature of the refrigerant discharged from the cooling coil for controlling the actuation of said expansion valve. 60

6. In a refrigerating system, a storage cham- 75
